[57] CLAIM

The ornamental design for a hand-holdable food processor, as shown and described.

DESCRIPTION

FIG. 1 is a side elevational view of a hand-holdable food processor showing our new design, the side opposite being a mirror image;

FIG. 2 is a top plan view;

FIG. 3 is a bottom plan view;

FIG. 4 is a front elevational view; and

FIG. 5 is a rear elevational view thereof.

The broken line showing of the recharge contacts in FIGS. 1, 2 and 3 is illustrative of environmental structure only and forms no part of the claimed design.
